US0D1093900S

(12) **United States Design Patent** (10) **Patent No.:** **US D1,093,900 S**
(45) **Date of Patent:** **** Sep. 23, 2025**

(54) **INSULATING DEVICE**

(71) Applicant: **YETI Coolers, LLC**, Austin, TX (US)

(72) Inventors: **Roy Joseph Seiders**, Austin, TX (US);
Christopher M. Keller, Austin, TX (US)

(73) Assignee: **YETI Coolers, LLC**, Austin, TX (US)

(**) Term: **15 Years**

(21) Appl. No.: **29/809,247**

(22) Filed: **Sep. 27, 2021**

Related U.S. Application Data

(63) Continuation of application No. 29/718,333, filed on Dec. 23, 2019, now Pat. No. Des. 931,614, which is a continuation of application No. 29/675,778, filed on Jan. 4, 2019, now Pat. No. Des. 871,074, which is a continuation of application No. 29/617,966, filed on Sep. 18, 2017, now Pat. No. Des. 882,956, which is a continuation of application No. 29/544,617, filed on Nov. 4, 2015, now Pat. No. Des. 797,454, which is a continuation of application No. 29/503,060, filed on Sep. 23, 2014, now Pat. No. Des. 787,187.
